UNITED STATES PATENT OFFICE

ALFRED R. NATHAN, OF NEW YORK, N. Y., ASSIGNOR TO HENRY HYMAN, OF BROOKLYN, NEW YORK

DESIGN FOR A CLOCK CASE

Application filed June 10, 1932. Serial No. 44,045. Term of patent 14 years.

To all whom it may concern:

Be it known that I, ALFRED R. NATHAN, a citizen of the United States, residing at New York city, in the county and State of New York, have invented a new, original, and ornamental Design for a Clock Case, of which the following is a specification, reference being had to the accompanying drawing, forming a part thereof, in which—

Fig. 1 is a front view of a clock case showing my new design; and

Fig. 2 is a side view of the same.

I claim:

The ornamental design for a clock case, as shown.

ALFRED R. NATHAN.
